INTERCHANGEABLE SHAFT FOR ELECTRICAL DEVICES

Marion J. Arvin, Indianapolis, Ind., assignor to
 P. R. Mallory & Co., Inc., Indianapolis, Ind., a
 corporation of Delaware

Application October 7, 1937, Serial No. 167,716

6 Claims.

(Cl. 64—4)

This invention relates to control shafts for electrical devices such as variable resistances for use in radio sets.

An object of the invention is to improve the arrangement of such shafts and particularly to render said shafts replaceable or interchangeable.

Other objects of the invention will be apparent from the following description and accompanying drawing taken in connection with the appended claims.

The invention comprises the features of construction, combination of elements, arrangement of parts, and methods of manufacture and operation referred to above or which will be brought out and exemplified in the disclosure hereinafter set forth, including the illustrations in the drawing.

In the drawing:

Figure 1 is a side view of a replaceable control shaft according to the invention;

Figure 2 is a sectional view of a variable resistance device adapted to receive said shaft;

Figure 3 shows the shaft and resistance device assembled and provided with an actuating knob;

Figure 4 is a section on the line 4—4 of Figure 3; and

Figure 5 shows the end of a modified form of shaft.

The radio receiving sets manufactured today vary in their parts requirements. For instance, one set will require a variable resistance device of one resistance value and terminal arrangement while another set has very different requirements. Likewise many different lengths of control shafts are required and these also vary in construction according to the kind of knob attachment desired. One shaft may be desired with a round end and another with a flat end and so forth. There are at least ten kinds of variable resistors needed to fulfill all the requirements and each type must be furnished with perhaps ten varieties of shafts.

Heretofore the shafts have been made an integral part of the resistance device and hence, to meet all the needs of manufacturers and radio service men about one hundred different models had to be carried in stock.

I have invented an interchangeable shaft arrangement whereby any desired shaft may be attached to any type of variable resistance. This makes it possible to meet all requirements by carrying in stock only about ten kinds of shafts and ten kinds of resistance devices.

While a preferred embodiment of the invention is described herein, it is contemplated that con-

siderable variation may be made in the method of procedure and the construction of parts without departing from the spirit of the invention. In the following description and in the claims, parts will be identified by specific names for convenience, but they are intended to be as generic in their application to similar parts as the art will permit.

Referring to the drawing, the preferred shaft 10 comprises a cylindrical piece of metal with parts cut away at one end to leave a flat tongue 11 having a pair of notches 12 in opposite edges. The knob end of the shaft may be formed in any desired way to accommodate a knob 23, for instance by providing a flat face 13 against which a set screw may bear.

The resistance device may comprise a case 14 containing an arcuate resistance element 15 and a rotatable contact arm 16 adapted to travel around said element in contact therewith to vary the amount of resistance in a circuit in a well known manner. Arm 16 is suitably secured to the inner end of a stub shaft 17 which extends through a bushing 20 affixed in the wall of case 14.

Stub shaft 17 extends just beyond the open end of bushing 20 and is provided with an annular groove 29 around the projecting portion within which a clinch ring 19 is fitted to prevent stub shaft 17 from sliding into the bushing.

The end of stub shaft 17 is slotted to a depth corresponding to tongue 11 on shaft 10, the slot 18 thereby extending back within the bushing for a considerable distance. The slot 18 is of such dimension as to fit over tongue 11 when the two shafts are brought together. It is preferred that the two end prongs of stub shaft 17 be bent together slightly so as to provide a spring-like clamping of tongue 11 when it is inserted in slot 18.

The length of tongue 11, and hence the depth of slot 18, should be greater than the diameter of shafts 10 and 17 to secure good bearing within the bushing and eliminate play and looseness.

Clinch ring 19 is provided in elliptical form (as shown most clearly in Figure 4) so that it will hold stub shaft 17 in place but the long diameter of ring 19 is sufficient to allow tongue 11 to be inserted in slot 18. When the two shafts are fully assembled, as shown in Figure 3, the notches 12 in tongue 11 will be aligned with groove 29 in stub shaft 17 so that clinch ring 19 locks them together. It will be evident that the shafts could only again be separated if the ring 19 were centered with its long axis parallel to the tongue 11.

a most unlikely occurrence especially when the shafts are mounted horizontally, as is usual.

If desired, of course, the ring 19 may be clinched after assembly.

5. Figure 5 shows a modified shaft 24 having a trifurcated tongue 25, 26, 27 with the center prong 26 offset from the others to provide a springlike bearing area upon insertion into the slot in the stub shaft. A notch 28 is provided to receive the 10 lock ring 19.

The improved shaft arrangement is applicable to shaft controlled electrical devices generally, such as variable resistance devices, rheostats, volume controls, potentiometers, switches, variable 15 condensers, and the like.

15. The shafts may be manually or automatically controllable, long, short, flexible, rigid and formed of metal or other material.

20. The arrangement provides an interchangeable, attachable, detachable shaft assembly which, when assembled will give positive action, free from backlash and excessive play, and which is positively locked together.

25. While the present invention, as to its objects and advantages, has been described herein as carried out in specific embodiments thereof, it is not desired to be limited thereby but it is intended to cover the invention broadly within the spirit and scope of the appended claims.

30. 30. What is claimed is:

1. A control shaft coupling for adjustable electrical devices comprising a pair of circular shaft sections of substantially the same diameter having interlocking portions for connecting them together end-to-end, one of said portions having a slot extending back from its end and having a 35 groove extending around said slotted region, the other of said portions comprising a tongue fitting into said slot, said tongue having edge notches in register with said groove when said shafts are in interlocked relation, and a clinch ring in said 40 registering groove and notches locking said shafts together.

2. A control shaft coupling for adjustable electrical devices comprising a pair of circular shaft sections of substantially the same diameter having interlocking portions for connecting them together end-to-end, one of said portions having a slot extending back from its end and having a 45 groove extending around said slotted region, the other of said portions comprising a tongue fitting into said slot, said tongue having edge notches register with said groove when said shafts are in interlocked relation, and a clinch ring in said 50 registering groove and notches locking said shafts together, and a tubular bushing surrounding said slotted shaft section adjacent said clinch ring, said clinch ring comprising a flange preventing

axial movement of said slotted section into said bushing.

3. A control shaft coupling for adjustable electrical devices comprising a pair of circular shaft sections of substantially the same diameter having interlocking portions for connecting them together end-to-end, one of said portions having a slot extending back from its end and having a groove extending around said slotted region, the other of said portions comprising a tongue fitting into said slot, said tongue having edge notches in register with said groove when said shafts are in interlocked relation, and a clinch ring in said registering groove and notches locking said shafts together, said tongue comprising a plurality of prongs affording spring bias against the walls of said slot to take up play and backlash in said coupling.

4. A control shaft coupling for adjustable electrical devices comprising a pair of circular shaft sections of substantially the same diameter having interlocking portions for connecting them together end-to-end, one of said portions having a slot extending back from its end and having a groove extending around said slotted region, the other of said portions comprising a tongue fitting into said slot, said tongue having edge notches in register with said groove when said shafts are in interlocked relation, and a clinch ring in said registering groove and notches locking said shafts together, said clinch ring being elliptical in shape to permit coupling of said shafts.

5. A control shaft coupling for adjustable electrical devices comprising a pair of shaft sections having interlocking portions for connecting them together end to end, said portions comprising non-circular interfitting parts fitting together to form a substantially circular joint, said interfitting parts being correspondingly grooved to provide a circumferential groove in said joint, and a clinch ring in said groove locking said sections together.

6. A control shaft coupling for adjustable electrical devices comprising a pair of shaft sections having interlocking portions for connecting them together end to end, said portions comprising non-circular interfitting parts fitting together to form a substantially circular joint, said interfitting parts being correspondingly grooved to provide a circumferential groove in said joint, and a clinch ring in said groove locking said sections together, and a tubular bushing surrounding said joint adjacent one side of said clinch ring, said bushing serving to maintain said shafts properly aligned and concealing a portion of said joint, said clinch ring providing a flange preventing axial movement of said joint further into said bushing.
